UNITED STATES PATENT OFFICE

WILLIAM W. WALLACE, OF CHICAGO, ILLINOIS, ASSIGNOR TO NEW YORK BRICK HANDLING CORPORATION, OF NEW YORK, N. Y., A CORPORATION OF NEW YORK

DUMPING FORK

Application filed June 7, 1927. Serial No. 197,027.

REISSUED

My present invention relates to brick handling devices, and more particularly to an improved dumping fork.

With the advent of railroad container cars and the rapid use of such cars in the transportation of the finished brick from the yard to the delivery point or destination thereof, considerable difficulty has been experienced in utilizing mechanical loading and unloading devices to economically fill such containers. To economically fill such containers with mechanically handled brick, it is practically necessary for the lifting or dumping fork with its load or unit of brick to be deposited in such container and gently placed to unload the unit load of brick in the bottom of the container. The containers being relatively small and the lifting fingers of the ordinary dumping fork being rigid with respect to the frame of the lifting or dumping fork, there is not room to retract the lifting fork from the unit of brick. Where a lifting or dumping fork with pivoted fingers is employed, there is so large a fulcrum or leverage 25 to permit retracting of the lifting fingers in dumping the load that it is impossible to utilize such construction in a confined space such as is found in container cars. Further, the operating means for tripping the lifting 30 fingers is ordinarily arranged to operate from below the fork rather than from above the same. There is, therefore, so far as I am aware, no dumping fork which can be successfully employed in loading container cars 35 with brick or other like construction.

In my present invention I have obviated the difficulties enumerated above with respect to former types of dumping forks and have 40 produced a dumping fork in which the fingers are pivotally arranged at the lower end of the fork frame and the increased leverage necessary to successfully lock the fingers in normal or rigid position is obtained by utilizing the force necessary to lift the load or unit of brick itself and when once locked, the weight of the load will retain the fingers in locked position.

By this construction, a dumping fork is 50 provided wherein the mechanism extending

to the rear of the fork or fork frame is a minimum and such fork may be operated in a small space. Further, the operating mechanism for releasing the pivoted lifting fingers to thereby allow the unit load of brick to be deposited within the container may be operated from either above or below the lifting fork, and, therefore, one of the chief difficulties is successfully overcome.

To facilitate entering the fork under the unit of brick, the portion of the lifting fingers to the rear of the actual lifting surface is beveled back, as such construction assists in entering the fork under the unit of brick when the front ends of the fingers are somewhat elevated. Again, the outer ends of the lifting fingers are arranged higher than the ends of the fingers adjacent to the fulcrum thereof, as with such construction the load is naturally balanced toward the back of the machine and thus bricks are prevented from falling off the unit. I have further found it desirable to provide guard plates, both for the front of the frame carrying the lifting fingers and for the rear thereof, as such frame protects the various devices from injury by the bricks themselves and from injury by engagement with the walls of the container.

The principal object of my invention, therefore, is an improved dumping fork.

A further object of my invention is an improved dumping fork having a plurality of parallelly arranged and pivoted lifting fingers.

A still further object of my invention is an improved dumping fork provided with locking means for the pivoted lifting fingers.

Another object of my invention is an improved guard device for protecting the operating mechanism of a dumping fork.

A further object of my invention is an improved construction whereby a unit load of brick will be carried in a position to prevent the outer bricks thereof from falling.

Other objects and novel features of the construction and arrangement of parts comprising my device will appear as the description of the invention progresses.

In the accompanying drawings illustrating preferred embodiments of my invention,

Fig. 1 is a side elevation;

Fig. 2 is a plan view;

Fig. 3 is a front elevation;

Fig. 4 is a rear elevation;

Fig. 5 is a section on the line 5—5 of Fig. 2;

Fig. 6 is a section on the line 6—6 of Fig. 2, and

Fig. 7 is a section on the line 7—7 of Fig. 2.

Referring to the drawings, 10 designates a finger bar in which is secured adjacent its lower end a finger hinge rod 11, and on such finger hinge rod is pivotally mounted a plurality of parallelly arranged lifting fingers 12. Formed integral with and extending upwardly from the body of the finger bar 10 are braces or brackets 13, to which are secured by bolts 14 brace rods 15 of suitable length. Secured to the top of such brace rods 15 by bolts 16 are top frames 17. The top frames 17 are arranged in pairs and each pair has secured at its rear end a shackle lug plate 18, such plates having formed integral therewith shackle lugs 19. Secured to each of the shackle lug plates 18 and extending downwardly and substantially vertically are guard angles 20.

Secured in each pair of top frames 17 is a fulcrum shaft 21 and on which fulcrum shaft 21 is rotatably mounted a dumping fulcrum 22. Pivotally attached to the outer free end of each dumping fulcrum 22 is a lifting shackle 23 connected by a shackle 24 to a bar 25 that may be attached to any suitable lifting device. Further, pivotally attached to each shackle lug 19 is a lifting shackle 26 pivotally attached to a shackle 27 attached to a bar 28 on the lifting device associated with the bar 25. The shackles 23 and 26, together with the associated members therefor, form a four-point suspension for the apparatus. The other ends of the dumping fulcrums 22 are forked, as indicated at 29, such other ends being part of the dumping fulcrum 22 and formed integrally therewith, and in each forked end is pivotally attached the upper end of a compression rod 30. The lower ends of these fulcrum rods 30 are threaded to receive adjusting nuts 31 and pass through inwardly extending lugs 32 formed integral with and on one face of a finger plate 33. The finger plate 33 is provided on its lower end with a shaft 34, such shaft passing through and pivotally engaging with aligned perforations in a rearward extension 35 on each of the lifting fingers 12. As the fulcrum levers 22 are rotated on the fulcrum shaft 21, reciprocating motion is imparted to the compression rods 30 and a simultaneous pivoting movement of the lifting fingers 12 takes place about the finger hinge shaft 11.

Secured to the opposing faces of the inner ones of the pairs of top frames 17 in any

suitable manner is a top frame connecting plate 36 and secured to the upper surface of the member 36 and the top frame 17 is a locking latch frame 37, this locking latch frame having formed therein a bearing for a locking shaft 38. Secured to the upper face of the member 36 is a locking latch shaft box 39 acting as a bearing and as a support for the front end of the locking shaft 38. Secured to the rear end of the locking shaft 38 is a locking lever hub 40, on which is formed a downwardly extending member 41 and an upwardly extending socket member 42. Secured to the member 41 by bolts 43 is a lever 44 and by means of which the locking shaft 38 may be rotated. The socket 42 is adapted to receive the end of any suitable lever and by means of which the shaft 38 may be rotated from the upper end of the apparatus. Formed in the front face of the locking latch frame 37 is a guideway in which is slidably mounted on either side of the locking shaft 38, locking latches 45. Secured to the locking shaft 38 adjacent to the front face of the locking latch frame 37 is a locking latch crank 46, and this crank has pivotally mounted at either end thereof a connecting rod 47. The other ends of these connecting rods 47 are pivotally attached to the locking latches 45. Rotation of the locking shaft 38 will cause a reciprocatory inward or outward movement of the locking latches 45 with respect to such shaft 38 and in alignment with the path of movement of such locking latches is a locking notch 48 formed in the forked end 29 of the dumping fulcrums 22.

When the parts of the device, therefore, are in the position shown in Fig. 5, with the dumping fulcrum 22 practically horizontal and with the locking latches 45 in their outward position to engage with the notches 48 in the rear ends of such dumping fulcrums 22, the plurality of parallelly arranged lifting fingers 12 will be in the full line position shown in Fig. 1, and when thus arranged, a rod may be placed thereon and carried thereby without danger of dumping the rod accidentally. If, however, the lever 44 is operated to rotate the shaft 38 in the proper direction, or if a lever is inserted in the socket 42 to rotate such shaft 38 in the proper direction, the locking rods 45 will be retracted or moved inward with respect to the notches 48 and if the strain is taken off the lifting devices to which the bars 25 and 28 are attached, the weight of the load of brick or other material on the lifting fingers 12 is sufficient to rotate the lifting fingers 12 about the finger hinge shaft 11 and as the apparatus is lifted upwardly, such lifting fingers will assume the position indicated in dotted lines in Fig. 1. It will be noted that the distance from the finger hinge rod 11 rearwardly to the shaft 34 on the finger plate 33 is very short, and, therefore, the overall dimension of the device

is a minimum. This allows the apparatus to be operated in a relatively small space. When the device is lowered into a container, injury to the operating parts is prevented by the 5 guard angles 20, which will engage with the side or ends of the container and serve to guide the apparatus into and out of such container. I find it preferable to attach to the front face of the finger bar 10 and the vertical brace bars 15, a baffle plate 50 in any suitable manner to prevent bricks or other articles from falling off the load into the mechanism at the rear of the apparatus.

As there is a certain amount of spring in the frame and in the carrying fingers 12, it is 15 necessary to provide adjustment for taking care of this condition in order that the fingers may be in their proper position after a load is placed thereon. In order that this may be 20 accomplished, I utilize on the threaded ends of the rods 30, adjusting nuts 31 which engage with the lugs 32. Therefore, by properly adjusting the nuts 31 on the rods 30 and with 25 relation to the lugs 32, the angular position of the lifting fingers 12 with respect to the framework may be varied as desired. The use of the adjustable fulcrum lever or compression rod, as above described, is, as far as I 30 am aware, new and novel and I propose to claim the same broadly.

By referring to Fig. 3, there will be noticed a dot and dash line 51, which coincides with the top rear edge of the lifting fingers 12, and further, it will be noticed that such line 51 35 is a curved line and indicating with the upper surface or edge of the lifting fingers 12 defines a concave surface or path. It is obvious, therefore, that when a rectangular unit of brick is lifted on the fingers 31, that the middle portion of such unit of brick will rest at 40 a lower level than the outer portions of such unit and there will, therefore, be a tendency for the outer upper edges of the bricks of the unit to move inwardly. This construction, 45 therefore, steadies the unit of brick on the fork and prevents the outer bricks of the unit from falling.

While I have necessarily shown and 50 described the preferred embodiment of my invention somewhat in detail, it is to be understood that I may vary the size, shape, and arrangement of parts comprising the device within side limits without departing from the spirit of the invention.

55 In my copending application, Serial No. 204,217, filed July 8, 1927, I have described and claimed an improved method of operating the fork constituting my present invention.

60 Having thus described my invention, what I claim as new is:

1. An improved dumping fork comprising a base, a plurality of lifting fingers pivotally attached thereto for rotation in vertical planes into and out of horizontal posi-

tion, lifting mechanism associated therewith, and means associated with the lifting mechanism for rotating said lifting fingers about their pivot point.

2. In an improved dumping fork, the combination of a base, a plurality of lifting fingers arranged parallel to each other, and pivotally attached at a point intermediate their ends to the base, a finger plate pivotally attached at one end to one end of the lifting fingers, a fulcrum lever, connections between the fulcrum lever and the finger plate, and a locking device associated with said fulcrum lever for locking the lifting fingers in operative position.

3. In an improved dumping fork, the combination of a framework, a fulcrum lever pivotally mounted intermediate its ends at the top of said framework, a plurality of parallelly arranged lifting fingers pivotally mounted intermediate their ends at the bottom of said framework, connections extending between the lifting fingers and fulcrum lever, and a manually operable locking device mounted on said framework and co-acting with the fulcrum lever for locking the lifting fingers in operative position.

4. In a dumping fork, the combination of a framework, lifting mechanism associated therewith, a plurality of lifting fingers pivotally mounted on the framework, controlling means associated with the lifting mechanism for positively operating said lifting fingers, and guard members mounted on said frame for preventing injury to the operating mechanism.

5. In an improved dumping fork, a plurality of pivotally arranged lifting fingers lying parallel to each other, and with the upper edges of each succeeding finger from the outside inward with respect to the plurality of fingers of less height than the preceding finger.

6. In an improved dumping fork, the combination of a framework, a plurality of lifting fingers pivotally attached thereto at the lower end thereof, said fingers defining by their upper edges a practically concave surface.

7. In an improved dumping fork, the combination of a framework, a plurality of lifting fingers pivotally attached thereto and movable in a vertical plane, controlling mechanism for said lifting fingers pivotally mounted on the framework, said controlling mechanisms being adjustably attached to the lifting fingers, whereby the angle of the lifting fingers with respect to the framework may be adjusted at will.

In testimony whereof, I have signed my name to this specification.

WILLIAM W. WALLACE.
